CLAIM

The ornamental design for a end portions of a double-ended wrench, as shown.

DESCRIPTION

FIG. 1 is an elevational view of the end portions of a double-ended wrench showing one end of my new design, the opposite end being omitted for ease of illustration only;

FIG. 2 is a top perspective view of the same end thereof;

FIG. 3 is a top perspective view of the opposite end thereof;

FIG. 4 is a bottom plan view of the end portions of a double-ended wrench showing my new design;

FIG. 5 is a side elevational view thereof;

FIG. 6 is a top plan view thereof;

FIG. 7 is an opposite side elevational view thereof;

FIG. 8 is an elevational view of the end portions of a double-ended wrench showing the end opposite that which appears in FIG. 1;

The handle and fasteners are shown in broken lines for illustrative purposes only and form no part of the claimed design.
